FASTENER

Thomas F. Coins, Henryetta, Okla.

Application August 23, 1932. Serial No. 630,104

2 Claims. (Cl. 292—106)

This invention relates to fasteners and its general object is to provide a latch primarily designed for fasteners of the hook type, which are generally employed for securing screen doors, window screens and the like, and when use is made of my latch with a hook fastener, it is impossible to open the fastener from the outside of the door, screen or the like, as the latch securely holds the hook in its eye.

10 A further object of the invention is to provide a fastener latch that is easy to apply, is simple in construction, inexpensive to manufacture, and extremely efficient in operation and service.

This invention also consists in certain other 15 features of construction and in the combination and arrangement of the several parts, to be hereinafter fully described, illustrated in the accompanying drawing and specifically pointed out in the appended claims.

20 In describing my invention in detail, reference will be had to the accompanying drawing wherein like characters denote like or corresponding parts throughout the several views, and in which:—

25 Figure 1 is a vertical sectional view taken through a screen door and illustrates the application of my latch to the fastening means of said door.

Figure 2 is an enlarged fragmentary sectional 30 view illustrating the application of my latch.

Figure 3 is a sectional view taken approximately on line 3—3 of Figure 2.

Figure 4 is a side view of the latch member 35 which forms a part of the present invention.

Figure 5 is an end view thereof.

Figure 6 is a perspective view of the latch plate.

Referring to the drawing in detail, the letter A indicates a screen door, B the stop strip therefor and C the door frame. While I have illustrated the application of my invention to a screen door, I want it understood that it can be applied to any type of door or window closing means without departing from the spirit of the 45 invention. The fastener generally employed for screen doors and the like includes a hook member D that is fixed to the door, and an eye screw E that is fixed to the stop strip as best shown in Figure 2, and my device is designed for holding the hook member in the eye screw as shown.

The latch plate of my device is indicated by the reference numeral 1 and while this plate may be of any shape, it is preferably square as clearly shown in Figure 6. The plate is provided with a 55 plurality of openings, two of which are parallel

with respect to each other and arranged adjacent one edge of the plate, and the other opening is arranged adjacent the opposite edge and is adapted to receive a fastening means in the form of a screw, for securing the plate to the stop strip, above and in contacting engagement with the eye screw as best shown in Figure 3.

Mounted for slidable movement in either of the parallel openings is the latch member which consists of a shank 2, and as one of these openings is adapted to be aligned with a bore 3 that extends through the stop strip and the frame as shown in Figure 2, the shank 2 is mounted for slidable movement in the bore and held accordingly therein by ears 4 that are arranged upon diametrically opposite sides of the shank and substantially midway its ends, as shown in Figure 4. The object of providing two openings to receive the shank of the pin, is so that the latch plate can be accommodated on stop strips and door frames of various widths. By disposing one opening off center, that opening can be used on either side, merely by reversing the plate, with the result there will be three positions to place the plate, with an opening aligned with the bore.

Formed with or otherwise secured to the outer end of the shank 2 is a disk 5 that is eccentrically mounted with respect to the shank and in fact is secured to the shank adjacent the periphery of the disk so as to not only cover the end of the eye screw as shown in Figure 3, but will drop by gravity for that purpose, from the dotted line position as shown in that figure to the full line position.

From the above description and disclosure of the drawing, it will be obvious that I have provided a latch that is primarily designed for hook fasteners and when it is in its normal position, the latch member is disposed in a manner whereby the disk 5 is arranged out of the path of the hook member D as indicated in dotted lines in Figure 3. However, when the latch member is in operative position, the disk 5 is disposed to engage the outer side of the eye screw E, with the result the shank 2 will be arranged in the path of the hook member D and positively prevent the hook member from being moved out of the eye screw, with the result it is impossible to open a screen door, screen or the like from the outside thereof when use is made of my latch with the fastening means of the said door, screen or the like.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A latching device for a hook fastener comprising a plate adapted to be secured adjacent to the eye screw that receives the hook fastener, 10 a latching means including a shank mounted for slidable movement through the plate, means to limit the slidable movement, a disk eccentrically mounted on the outer end of the shank to drop by gravity and be held accordingly in engagement 15 with the eye screw in a manner whereby the shank is disposed above the hook to prevent the removal of the latter from the eye.

2. In a latching means for a hook fastener including an eye, a plate adapted to be secured to the stop strip of a door, said stop strip and door being provided with a bore, said plate being provided with openings and capable of being adjustably mounted with one opening aligned with the bore, a latch means including a shank mounted for slidable movement through the opening and into the bore, ears formed on the shank and being engageable with the plate to limit the outward movement of the shank, and a disk eccentrically mounted on the outer end of the shank to drop by gravity and be held accordingly in engagement with the eye and to cooperate with the shank to prevent the removal of the hook of the hook fastener from its eye. 80 85 90
